(57) CLAIM

The ornamental design for a faucet for sanitary installations, as shown and described.

DESCRIPTION

FIG. 1 is a side elevational view of a faucet for sanitary installations, showing my new design;

FIG. 2 is a view thereof from the side opposite that shown in FIG. 1;

FIG. 3 is a rear elevational view thereof;

FIG. 4 is a top plan view thereof; and,

FIG. 5 is a top, front and side perspective view thereof, with the parts in a different position.
